UNITED STATES PATENT OFFICE.

JOHN B. MASERANG, OF BELLEVILLE, ILLINOIS.

RAILWAY TIE.

Application filed June 20, 1928. Serial No. 286,757.

This invention relates to new and useful improvements in railway devices, and particularly to railway ties and rail fasteners.

One object of the invention is to provide a railway tie which is strong and durable and which can be manufactured at a comparatively low cost.

Another object is to provide a device of this character wherein the rails may be properly adjusted toward and away from each other, to permit laying railways of different gauges.

Another object resides in the provision of novel and improved means for attaching or securing the rails to the tie.

Other objects and advantages will be apparent from the following description when taken in connection with the accompanying drawings.

In the drawings:

Figure 1 is a top plan view of a tie and rail fastening device, made in accordance with the present invention, one corner of the tie being broken away.

Figure 2 is a vertical transverse sectional view on the line 2—2 of Figure 1, a bolt being removed.

Figure 3 is a vertical longitudinal sectional view on the line 3—3 of Figure 1.

Referring particularly to the accompanying drawing, there is shown a tie, represented as a whole by the numeral 10, and comprising the hollow body 11, formed with the longitudinal channel 12, extending centrally of the upper face thereof, and having the laterally directed, and longitudinally extending flanges 13. The flanges are provided with pairs of openings 14, to which reference will be made later herein. Attached to each end of the body 11, and at opposite sides thereof, by means of the rivets 15, are the end closure plates of the tie body, shown at 16. Each of the side walls of the channel 12 is formed with the series of notches 17.

Disposed across the upper face of each end of the tie is a plate 18, the ends of which are provided with openings registering with the openings of the flanges of the tie, to receive the bolts or rivets 19 therethrough, for the purpose of securing such plates to the tie.

Formed on the intermediate portion of the lower face of each of the plates 18 is a block 20, the two opposite sides of which are formed with the teeth 21, which are received in the notches 17. Formed through the said block 20, in a direction longitudinally of the tie, are the three openings 22, one end of

the central one having a vertical recess 23, opening through the upper face of the plate, while the two outer openings have their other ends correspondingly formed with recesses 24, but at sides opposite to that of recess 23. The upper face of each of the plates 18 is roughened, and seated on each of the plates, transversely of the tie, is a railway rail 25. Disposed in each of the openings 22 is a bolt 26, such bolts being inserted in the openings from the recessed ends thereof, so that their threaded portions extend into the cylindrical portions of said openings, and beyond the opposite end of the block portion 20, where a nut 27 is engaged thereon. The other end of each of the bolts 26 is provided with a head 28 which snugly fits into one of the recesses 23—24. On this head, and rising vertically therefrom, there is formed the threaded stem 29, which projects upwardly through the portion of the recess which enters the upper face of the plate. Engaged on this stem or stud 29 is a nut 30, the lower face of which is formed in conformity with the inclined upper face of the base of the rail, and is arranged to bear down on such base to hold the rail in position on the plate. This nut is of the castle type and receives the upper end of the key 31, which is disposed in the groove 32 of the stem or stud 29. The nuts which are engaged on the threaded ends of the bolts 26 are similarly provided with locking features.

By means of the teeth and notches of the tie and plate, the rails may be moved toward and away from each other, in accordance with the gauge of the railway with which the device is being used.

What is claimed is:

1. A railway device comprising a tie having a channel, notches in the walls of the channel, a rail chair having teeth interchangeably engageable in the notches, means for securing the chair to the tie, and means carried by the chair for clamping engagement with a rail base.

2. A railway device comprising a tie having a longitudinal channel the side walls of which are provided with notches, a plate disposed transversely of the tie and having a depending toothed member engaged with the notches of the tie, means for securing the plate to the tie, and rail engaging clamping bolts disposed through said depending toothed member.

3. A railway device comprising a tie having a longitudinal channel in its upper face,

the side walls of the channel being formed with notches, a rail supporting plate disposed across each end portion of the upper face of the tie, each of said plates having a depending block portion provided with marginal teeth engaged with the notches of the walls of the channel, the ends of the plate being detachably secured to the tie, said block portion having a plurality of longi-

tudinal openings formed therethrough, one end of each of said openings being formed with a recess, a bolt disposed in each of said openings and having a head portion fitted into a recess of an opening, a vertical threaded stud formed on said head, and a rail base 15 engaging nut engaged on said stud.

In testimony whereof, I affix my signature.

JOHN B. MASERANG.
